UNITED STATES PATENT OFFICE.

ARTHUR M. HOUSER, OF CHICAGO, ILLINOIS, AND WILLIAM B. MORRIS, OF PHILADELPHIA, PENNSYLVANIA, ASSIGNEES TO CRANE COMPANY, OF CHICAGO, ILLINOIS, A CORPORATION OF ILLINOIS.

FLUSHING APPARATUS.

1,408,883.

Specification of Letters Patent. Patented Mar. 7, 1922.

Original application filed December 21, 1917, Serial No. 208,204. Divided and this application filed September 20, 1920. Serial No. 411,512.

To all whom it may concern:

Be it known that we, ARTHUR M. HOUSER and WILLIAM B. MORRIS, citizens of the United States, and residents of Chicago,

5 Illinois, and of Philadelphia, Pennsylvania, respectively, have invented certain new and useful Improvements in Flushing Apparatus, of which the following is a specification.

10 This invention relates in general to valve operating mechanism and has more particular reference to foot-actuated apparatus designed for the purpose of operating a closet bowl flushing valve, this application constituting a division of our prior application, 15 Serial No. 208,204, filed December 21, 1917.

One of the primary objects of our present invention is to provide a flushing apparatus of the character indicated, which will be 20 simple in construction, cheap to manufacture, easy to install, and one which will be reliable in operation, convenient to assemble, and which is readily accessible for purposes of repair or replacement when necessary.

25 Other objects and many of the attendant advantages of our invention will be readily appreciated by those skilled in the art as the same becomes better understood by reference to the following description, when considered in connection with the accompanying drawings.

Referring to the drawings:

Fig. 1 is a plan view of a flushing apparatus embodying our invention, showing its manner of installation and method of connection to a flushing valve;

Fig. 2 is a fragmentary view, partially in section, of the apparatus disclosed in Fig. 40 1; and

Fig. 3 is a vertical sectional view taken at right angles to the showing of Fig. 2.

While our invention is applicable to flush valves of various types, we have shown on the drawings for purposes of illustration, a flush valve of well known construction, commercially referred to as the "Phillips flush valve" and it is designated on the drawings by reference character 4. This valve is connected at one end in the usual manner to the water supply pipe 5 and its outlet is connected to the bowl 6 by a pipe 7 which passes through the partition 8. On the

valve casing is mounted the lever 9, the arm 11 of which when raised, opens the valve 55 and brings the air check (not shown) which is disposed within the cylinder 12, into position where the subsequent discharge of the water toward the bowl is controlled in the customary manner until the valve closes, 60 whereupon the arm 11 is returned to normal position by the water pressure.

Our invention is designed for the purpose of actuating the lever 11 from the point in front of or at the side of the bowl and comprises apparatus adapted to be actuated by the foot for the purpose of operating the flushing device, and with this end in view, a floor box or casing 13 is set into the floor in convenient location with respect to the 70 bowl 6 and forwardly of the partition 8. The top of the casing is normally closed by a removable cover plate 14 secured in position by a plurality of screws 15 which are threaded into side lugs 16 formed on the 75 interior of the casing. This cover plate is provided near one end with a depending guiding sleeve 17 adapted to receive and guide in its vertical movements, the hollow stem 18 of a pedal push button formed at 80 its upper exposed end to provide an index cap 19 and threaded at its lower end to receive a stop ring or nut 21 by which the push button is retained against displacement from the cover plate. Near the opposite end of the casing and in the side wall 85 nearest the partition, there is formed a socket 23 interiorly threaded to receive the exteriorly threaded inner end of a tubular member 24 set below the upper surface of 90 the floor. The opposite wall of the casing is formed in alignment with the socket 23 with a bearing 25, and supported upon these aligned bearings, is the fulcrum hub 26 of a pedal lever or arm 27. The free end of this 95 lever is formed to provide a concave socket or depression 28 disposed in vertical alignment with the push button, and between this socket and the concave inner face of the index cap 19, there is loosely disposed a push rod or pin 29 through which downward thrust upon the button is imparted to the lever 27 without binding or cramping of any of the co-operating parts.

The hub 26 of the lever 27 is interiorly 105 shaped to receive the inner end of a rock

shaft 31 to which the hub is secured by a set screw 32. The outer end of this rock shaft projecting beyond the end of the tubular member 24 has secured thereon by a set screw 33, a lever 34 which extends laterally from the rock shaft and is pivotally attached at its outer end to a link 35 connected at its upper end with the lever arm 11, as shown in Fig. 1.

10 The casing 13 and the tubular member 24 being preferably permanently set in the concrete of the floor as shown, it will be manifest that they are stationarily secured and retained in desired position so that they are not subject to accidental displacement. The various operating parts are enclosed and protected against injury and by simply removing the screws 15, the top plate 14 of the casing can be lifted off so as to permit access to the interior of the casing for purposes of inspection, repairs, or replacement.

15 The lever 27 can be readily disconnected from the rock shaft by simply loosening the screw 32, which permits longitudinal withdrawal of this shaft from its casing 24, and as will be apparent, all of the parts can be quickly and easily assembled, and when united, provide a compact, efficient and serviceable apparatus for actuating a flushing valve.

20 It is believed that our invention, its manner of construction and assembly, and mode of operation will be understood from the foregoing without further description, and 35 while we have shown and described a preferred embodiment of the invention, it will be obvious that the various details are capable of wide modification and variation without departing from the essence of the invention, as defined in the following claims.

40 We claim:

1. In a flushing apparatus, the combination of a flushing valve, a casing adapted to be set in a floor, a rock shaft journaled in 45 said casing, said shaft being extended laterally through one wall of the casing beneath the upper surface of the floor to a point in proximity to said flushing valve, an arm secured to said extended end of the shaft, an operative connection between said arm and 50 said flushing valve, and means operable from outside said casing for actuating said rock shaft.

2. In a flushing apparatus, the combination of a flushing valve, a casing adapted 55 to be set in a floor, a rock shaft journaled in said casing, an arm secured to said shaft within the casing, means projecting through the top of the casing for actuating said arm, a hollow guide member attached at one end 60 to said casing and projecting laterally therefrom around said rock shaft, and means secured to the outer end of said rock shaft for operating said flushing valve upon actuation of said rock shaft. 65

3. In a flushing apparatus, the combination of a casing adapted to be set in a floor, a lever arm journaled within said casing, a removable top secured to the casing, an operating device extending through said top into operative relation with said arm, a rock shaft rigidly attached to said arm and projecting laterally from said casing, a tubular member surrounding said rock shaft and attached at one end to a side wall 75 of said casing, an arm secured to the outer end of said rock shaft, and a flushing valve actuating member connected to said arm. 70

4. In flushing apparatus, the combination of a floor anchored closure means, comprising a floor box having an inner bearing and provided with an elongated tubular member disposed in alignment with said bearing, and adapted to be supported in the floor, a 80 pedal actuated lever having its hub journaled in said bearing, and a fulcrum rod mounted to turn in said tubular member upon actuation of said lever, said rod having its inner end engaged in the hub of 85 said lever and its outer end exposed for 90 connection with a flushing valve operating member.

5. In flushing apparatus, the combination of a housing having an inner bearing and an elongated tubular member positioned in 95 alignment with said bearing and constituting an extension of said housing, a lever having its hub journaled in said bearing, a fulcrum rod mounted to turn in said tubular member upon actuation of said lever having 100 one end removably seated in the hub of said lever, the other end of the rod being adapted to be operatively connected with a flushing valve operating member.

ARTHUR M. HOUSER,
WILLIAM B. MORRIS.
